SHOE HEELING CLAMP

William H. McCaffrey, Minneapolis, Minn.

Application November 20, 1936, Serial No. 111,931

6 Claims. (Cl. 12—125)

This invention relates to a device for holding the heel and the heel end of a shoe in proper relative positions while the shoe and the heel are being nailed on or otherwise secured together.

5 The device is particularly adapted for attaching wooden heels to women's shoes and is constructed and designed for use in shoe repair shops. To this end, the invention embodies certain novel features of construction whereby it is especially 10 adapted for ready attachment to or removal from a work bench or a counter. In addition, the invention contemplates and provides novel means for clamping the heel and shoe in proper relative position without injuring or marring the heel or 15 shoe.

Additional objects of the invention are to provide a shoe clamp which is manually operated, simple and inexpensive in construction, and which is composed of few parts separably united 20 and compactly arranged.

With the foregoing objects in view, the invention consists in the novel construction and arrangement of parts hereinafter more fully described and pointed out with reference to the 25 accompanying drawings, wherein:—

Figure 1 is a side view of the shoe clamping device in operative condition, the heel end of a shoe and the shop counter being indicated in dotted lines.

30 Fig. 2 is a top plan view of the device.

Fig. 3 is a front end view thereof.

Fig. 4 is a fragmentary side view partly sectioned to disclose the heel clamping members.

Fig. 5 is a horizontal section on line 5—5 of

35 Fig. 1.

Fig. 6 is a fragmentary detail view of the front heel clamping member, partly in section.

In order that the device may be conveniently attached to and supported on the corner of a 40 bench or counter, such as indicated in dotted lines at 7, in Fig. 1, the various units are mounted on or made integral with a base plate 9 having laterally spaced lugs 10 and 10' depending from the under side thereof adjacent one end of the 45 plate in overhanging abutting relation with one edge of the counter or other support; the plate being fastened to the support by screws, bolts or other fasteners, inserted through the holes 11 in the plate. Integral with the plate and extending vertically of the upper side thereof is a 50 post having a T-shaped body portion 13 surmounted by a head 15 which is substantially square in cross section. The head 15 is grooved or recessed in its top side to provide spaced bearing lugs 17 and 17' which are apertured to receive

the ends of the fulcrum or pivot bolt 19 at one end of an arm 21, which is provided at its opposite or free end with a vertically disposed screw threaded bore in which is screwed a long clamping screw 23. The screw 23 is provided at its 5 upper end with a handle 25 and at its lower end with a swivelled work-engaging member 27. Arm 21 extends forwardly of the broad face or head of post 13 with its free or screw bearing end overhanging the end of the base plate having the 10 depending lugs 10 and 10'. By reason of its pivotal connection with post 15, the arm 21 is movable from a horizontal to a vertical position for substantially an arc of 90°, and at its pivoted end is provided with a stop lug 29 adapted to abut 15 the rear edge 31 of the post head 15 when the said arm is vertically disposed. Suitable means are provided for locking the arm 21 and clamping screw 23 in clamping position. The particular locking means illustrated comprises a plate 20 33 flexibly connected to the post by a string 35 and carrying a locking pin 36 insertable through aligned openings in the post bearing lugs 17 and 17'; the arm 21 having an aperture adapted to register with the pin receiving openings in the 25 post bearing lugs when the arm 21 is horizontally positioned as illustrated in Fig. 1. The T-shaped portion of the post serves as a vertical guide for the carrier 37 of the heel back clamping member 39. Carrier 37 comprises a tubular block having 30 its rear end cut out, as at 41, to receive the broad head of the T-shaped post 13. A pair of angle straps 43 and 43', preferably of spring metal, are attached by screws 45 to the rear end of carrier 39 so as to engage rearwardly of the head 35 of the post 13 and transversely of the rear flange thereof, as shown in Fig. 5; the said straps being secured at their outer ends by a ring bolt and nut assembly 47 whereby they may be clamped 40 against the post 13 to hold the carrier 37 stationary on the post. The clamping member 39 carried by the member 37 is preferably a wooden plug having its outer end concaved and arcuate to fit snugly against and around the back portion of a shoe heel 49. Several different types 45 of plugs 39 will be used separately with carrier 37 to accommodate different types of shoe heels, and the carrier is adjustable vertically of post 13 to enable the operator to set the plug or clamp 37 in exactly the right position against the back 50 of the shoe heel as the particular design and shape of the heel may require.

In advance of the back clamping member 39 and cooperably positioned relative thereto is a 55 front clamping assembly comprising a shaft 51

jounaled for rotation in lugs 10 and 10' of the base plate and having a crank arm 53 at one end. Shaft 51 is provided with a pair of through openings extending transversely therethrough and laterally spaced apart to be on the outsides of lugs 10 and 10', these openings being adapted to receive the legs of a U-shaped member or yoke 55 extending upwardly and around the front end of the base plate 9 so as to bear against the front portion of the shoe heel 49. Yoke 55 is adjustable relatively to shaft 51 and is fixed in any position to which it is adjusted by means of a binding screw 57 screwed into one end of shaft 51 and bearing against one leg of the yoke, as shown in Fig. 6. The means for rotating shaft 51 to place yoke 55 into and out of heel clamping position, consists of a hand lever 59 pivoted at 61 to a lateral extension 63 of the base plate and having its lower end pivotally connected at 65 to one end of a link 67 which has its opposite end pivotally connected at 69 to the crank 53 of the shaft. Movement of the handle end of lever 59 to the left of Fig. 1 causes the clamping yoke 55 to be swung away from the back clamping member 39 or into heel releasing position. Reverse movement of the lever causes clamp yoke 55 to press the heel firmly against the back clamping member 39, the opposite end of which is in abutment with the broad face of the T-shaped post 13. Fastened to the base plate 9 by bottom lug 71 and disposed concentrically with the axis of the lever 59, is a lever quadrant 73 having an arcuate slot 75 through which extends the shank of a headed bolt 77 carried by the lever 59 and having a wing nut 79 screwed on its inner end. When the wing nut is screwed up tight, the lever is clamped to the quadrant for preventing any movement of clamping member 55, and when the wing nut is loosened, the lever 59 may be swung freely within the limits of arcuate slot 75, for turning shaft 51 and swinging clamping member 55 into and out of clamping position.

In using the device, the wooden heel 49 is placed on base plate 9 and clamped between clamping members 55 and 39 by proper manipulation of lever 59. The shoe to which the wooden heel is to be attached is then positioned with the heel end of the shoe resting upon the top of the wooden heel 49 as indicated in dotted lines in Fig. 1 and the arm 21 is then swung into position so that the clamping screw 23 depends inwardly of the shoe with the bearing plate 27 pressing the heel end of the latter against the heel. The screw 23 is then rotated by the handle 25 to clamp the heel end of the shoe and the wooden heel in proper relative position. In this condition of the clamp, the first two nails are driven through the bottom of the shoe and into the heel in front of the bearing end 27 of the clamping screw 23. The latter is then turned and the locking pin 36 pulled out to release the arm 21 which may be then swung upwardly and out of the way. The process of attaching the heel and shoe is then finished by driving in the next three nails, there generally being five nails in all in the heel of a woman's shoe.

From the foregoing, it is thought that the operation and construction of the device will be readily understood.

70 What is claimed as new is:—

1. A shoe clamp comprising a base plate, a vertical guide post thereon, a slide on said post, a heel back clamping member carried by said slide, means for clamping said slide to said guide

post, a heel front clamping member on said plate and movable to and from proximity with the back heel clamping member, and a shoe clamping member mounted on said post and adjustable to a position for clamping the heel end of a shoe against a heel clamped between the said front and back heel clamping members. 5

2. A shoe clamp comprising a base plate, a perpendicular guide post thereon, a slide on said post, a removable member in said slide and extending horizontally outwardly therefrom in parallelism with the base plate with its outer end shaped to receive and to support the back portion of a shoe heel, a member pivotally mounted on said plate for engaging the front portion of a 10 shoe heel to clamp the latter against the member supporting the back of the heel, and an arm pivotally mounted in said post for adjustment toward and away from the heel clamping members, and a clamping screw at the free end of said arm 20 for clamping the heel end of a shoe upon the shoe heel. 15

3. A shoe heel clamping device comprising a base plate, a pair of heel clamping members mounted on said plate, one of said clamping members being mounted to turn about a fixed axis and the other member being mounted for adjustment vertically of the plate to accommodate heels of varying heights, a clamping screw adapted for insertion in the heel end of a shoe 25 for clamping same against the top portion of a shoe heel, clamped between the heel clamping members, means carrying said clamping screw and adjustably connected with said plate for moving said clamping screw into and out of shoe 30 clamping position, and individual means associated with the clamping units for locking them in clamping position. 35

4. A device for the purpose described, comprising a base plate, a heel holding member on the base plate and arranged to engage one side of a heel, a rock shaft carried by the base plate and equipped with a complementary heel holding member arranged to engage the opposite side of a heel and also equipped with a crank arm, a lever mounted on the base plate and connected with said crank arm, and means for adjustably fixing said lever. 40

5. A device for the purpose described comprising a base plate, a heel holding device thereon and arranged to engage one side of a heel, a fixed post on the base plate, a carrier adjustable vertically relatively to the base plate and post and equipped with means for adjustably fixing it to the post and having a forward open end, and a 50 plug arranged in and protruding forwardly from said carrier and toward the first-named heel holding device and having its forward end shaped conformably to a heel side. 55

6. A device for the purpose described comprising a base plate, a post fixed to and rising from said plate, a vertically swingable arm connected to said post and having a threaded bore, a screw arranged in said bore, a rock shaft carried by the base plate and having a bail for engaging one side of a heel and also having a crank, a hand lever connected with the base plate and connected with said crank, means for adjustably fixing said hand lever, a carrier adjustable vertically relatively to the base plate and the post and equipped with means for clamping to the post, and being open at its forward end, and a plug arranged in said carrier and adapted to bear against a heel. 60
